GUN COCKING DEVICE

Filed Sept. 16, 1942

UNITED STATES PATENT OFFICE

2,386,801

GUN COCKING DEVICE

Clifford E. Johnson, Medway, and Carleton R. Elliott, Dayton, Ohio

Application September 16, 1942, Serial No. 458,584

5 Claims. (Cl. 89—1)

(Granted under the act of March 3, 1883, as amended April 30, 1928; 370 O. G. 757)

The invention described herein may be manufactured and used by or for the Government for governmental purposes, without the payment to us of any royalty thereon.

This invention relates to gun cocking devices for association with a gun or cannon, to move the gun bolt to initial charged condition in engagement with its sear, preparatory to firing automatically.

It is the principal object of the invention to provide a simple and efficient cocking or charging unit which is interchangeable for association with different guns, the said unit being readily removable and replaceable for this purpose.

Another object of the invention is to provide a gun cocking or charging unit of the type referred to, which is universally adaptable for use with guns placed in different positions or locations in an aircraft, for instance, so as to enable operating connections to work in conjunction therewith from different desired directions according to the particular conditions encountered.

In carrying our invention into practice, we have provided a gun cocking device, or charging unit, which comprises a movable plunger adapted to engage and move the gun bolt to charging position, a fixed member including means for securing the same in fixed relation to the gun; yieldable means intermediate the plunger and the fixed member referred to, for normally urging the plunger away from said member; guide means secured to the fixed member for positioning and guiding the yieldable means, which, in the embodiment of the invention herein disclosed, comprises a helical spring embracing the guide means and extending into the plunger; and actuating means connected with the plunger and extending axially through the yieldable means, guide member, and fixed member.

The actuating means preferably includes a cable and a pulley over which the cable is trained, the pulley support being rotatable to different fixed positions on an axis parallel to the path of movement of the plunger so that the actuating means or cable may lead from the charging unit in any one of different desired directions, according to particular conditions of location of the gun respecting the operator's station.

The construction is such that yieldable means of maximum length may be employed, having regard to the limitations of dimensions of the elements of the charging unit, so that maximum pressure for maintaining the plunger in non-charging position against the recoil action of the gun in firing is secured, while at the same time resulting in a minimum build-up of pressure at the end of the charging stroke, so that the least possible manual effort is required to move the gun bolt to charged position.

The construction is such that the actuating

means is confined within the yieldable means and the guide member, so that there is no danger of its interference with the gun bolt.

The fixed member is provided with a slot accommodating that part of the gun bolt that is engaged by the plunger, so that the gun bolt may be removed past the fixed member for disassembly without disturbing the charging unit.

For assisting in maintaining the plunger in noncharging position against the recoil action of the gun, and in order that a yieldable means of a less compression build-up can be utilized, the invention contemplates that a magnet, fixed respecting the gun, may be provided for cooperation with the plunger.

Other objects, advantages, and features of novelty will become apparent as the description of the invention progresses in conjunction with the accompanying drawing, in which:

Fig. 1 is a view showing the cocking device of the invention in association with a gun, parts thereof being broken away and certain elements of the cocking or charging unit being shown in section;

Fig. 2 is a partial end elevation of a gun embodying the gun cocking device of the invention.

Fig. 3 is a sectional view taken on the line 3—3 of Fig. 1, looking in the direction of the arrows, the gun being shown broken away;

Fig. 4 is a perspective view of a part of the means for connecting the actuating means to the plunger, showing the manner of association of the actuating means therewith.

The invention is shown in conjunction with a gun, generally indicated by the numeral 1, provided at its side with a charger receiver housing portion 2 located adjacent the breech of the gun having a cylindrical bore 2a extending axially of the gun. The receiver housing 2 is provided with a longitudinal slot 3 through which the gun bolt 4 extends from the gun breech into the interior of the receiver housing 2. The slot 3 starts from a point intermediate the ends of the receiver housing 2 and extends clear to the rear end of said housing, as shown.

The cocking device, or charging unit, of our invention is adapted to be received within the receiver housing 2, and essentially comprises the following elements: A supporting, or abutment, member 5 of cylindrical form adapted to be received within the housing 2 and maintained in fixed relation respecting said housing by means of a set screw 6 threaded through a suitable aperture in the housing 2 and engaging a recess in the periphery of the member 5; a guide member 7 secured to the member 5; a plunger 8 fitting within the housing 2 and reciprocable respecting the same; yieldable means comprising a helical spring 9 embracing the guide member 7 and engaging the abutment member 5 and the plunger

8 so as to normally urge the latter away from said abutment member to maintain the plunger in non-charging position; and actuating means associated with the plunger for moving the same against the action of the yieldable means 9 to cause the plunger to engage and move the gun bolt 4 leftward, having reference to Fig. 1, to charging position, in which position the gun bolt is locked by engagement with its sear (not shown).

This actuating means, in the embodiment shown, comprises a cable and pulley means including a cable 10, secured to the plunger 8 and extending axially through the helical spring 9, guide member 7, and abutment member 5, and thence being trained over the pulley 11.

As illustrated, the plunger 8 may be hollow so as to receive the inner end of the helical spring 9, and the hollow interior of said plunger 8 may be provided with an abutment member for engaging the inner end of the spring 9, said abutment member comprising a plug 12 sweated into the inner end of the plunger 8 and provided with a tapered seat 12a for the reception of a tapered conical connecting member 13 designed for detachable connection with the cable 10. For this purpose the tapered member 13 is provided with an axial bore 13a and a radial slot 13b communicating therewith. The bore 13a is of sufficient diameter at the flared end of said member to receive the ball portion 14a of a ball fitting 14 secured to the end of the cable 10, and the bore 13a is of reduced diameter toward the narrow end of the tapered member 13 so as to just receive the cable 10 but prevent the ball portion 14a of the fitting 14 from passing through the bore 13a of the tapered member toward the narrow end of the latter. For this purpose the bore 13a may be provided with a shoulder 13c defining the reduced portion thereof, and against which the ball portion 14a abuts. The slot 13b is of sufficient width to permit the cable to pass therethrough so as to enable the ball portion 14a of the fitting 14 to be seated in the bore 13a of the tapered member 13.

Thus there is provided means for detachably connecting the cable 10 with the plunger 8, whereby the ball fitting 14 end of the cable 10 may be threaded through the plug 12 in a rightward direction, having reference to Figs. 1 and 4, and the cable then passed through the slot 13b of the tapered member 13 while the extremities of the latter are intermediate the plug 12 and the ball portion 14a, the latter being of a larger diameter than the slot 13b. Then the cable 10 may be moved leftward, having reference to Figs. 1 and 4, so that the ball portion 14a is positioned within the bore 13a of the tapered member 13 and the latter seated in the tapered seat 12a of the plug 12.

For the purpose of enabling the cable 10 to pass axially through the guide member 7 and the abutment member 5, the member 7 may conveniently comprise a hollow tube, sweated into a suitable socket provided in the member 5 so as to communicate with an axial passage 5a provided therein. The outer end of the member 5 is provided with a hollow bearing or boss 15, through which the cable 10 extends, as seen best in Fig. 1. Rotatably mounted on this boss 15 is a bifurcated bearing bracket or pulley block 16 (Figs. 1 and 2), extending between the legs of which is a suitable pin or shaft 17 upon which are mounted the pulley 11 and the stirrup 18 for guiding the cable 10 thereover. The bearing bracket 16 is

rotatable on the boss 15 about an axis parallel to the axis of the plunger 8, and said bracket is provided with a screw or pin 19 engageable with an annular groove 15a provided on the hollow boss 15, whereby to maintain the bearing bracket 16 against axial removal from the boss 15. Suitable means, such as the lock bolt 20 threaded through the legs of the bracket 16, is provided for clamping the bracket relative to the boss 15, to maintain said bracket against rotation around the boss when the desired rotational position of the bracket respecting the boss has been determined.

Thus, for instance, the bearing bracket 16 carrying the pulley 11 will be initially rotated around the boss 15 to a position determined by the direction in which the cable is to pass from the pulley to the operator's station. In this connection, it is contemplated that the gun with which the charging device of the invention is associated may be positioned at a location remote from the operator's station—as in the wing of an airplane, for example—and the direction in which the cable 10 extends from the pulley to the operator's station will determine the adjusted rotational position of the pulley bracket 16 respecting the boss 15.

For limiting the inward movement of the plunger 8 in the direction in which it is normally urged by the yieldable means 9, the receiver housing 2 may be provided at its forward end, as shown in Fig. 1, with a removable plug 21 with which the plug 12 end of the plunger 8 may engage. If desired, the plug 21 may incorporate a permanent magnet, as indicated at 22, cooperable with the plug 12 end of the plunger 8 to assist the action of the spring 9 in maintaining the plunger at its rightward extreme, noncharging, position in the housing 2 to insure against movement of the plunger respecting the housing in response to recoil action of the gun so that the plunger will not engage with the gun bolt lug 4 during firing, and, therefore, will not interfere with the proper action of the gun bolt 45 during such time.

However, it is to be noted that by reason of the design of the charging unit of our invention, in respect of the fact that a considerable portion of the length of the spring 9 extends into the plunger 8, a heavy spring 9 of sufficient length and strength to maintain the plunger 8 in non-charging position against the recoil action of the gun, may be utilized so as to eliminate the necessity for providing the magnet 22, while at the same time enabling the employment of a plunger 8 of sufficient length to provide proper bearing thereof within the receiver housing 2 and thus prevent any misalignment or cocking of the plunger in the housing such as might tend to 60 cause the plunger to bind or jam respecting the housing.

The provision of the extended tubular guide member 7 also assists in permitting a longer spring 9 to be used, since the same is adequately supported by said guide member 7. On account of the fact that the cable 10 is confined within the spring 9 and the guide member 7, said cable is prevented from interfering with the operation of the gun bolt lug 4 during firing.

The abutment member 5 is provided with a longitudinal recess 5b extending from end to end and adapted to accommodate the gun bolt lug 4 so as to enable the same to be moved past the member 5 outwardly (left-wardly respecting Fig. 1) for disassembly without disturbing the

charging unit. For the purpose of removal of the breech block including the gun bolt, the end plate 1a of the gun must, of course, be first removed.

If desired, stops 23 may be provided on the abutment member 5 for engagement with the bearing bracket 16 to limit the rotational movement thereof with respect to the boss 15.

In operation, for initially cocking the gun or moving the gun bolt into position to be engaged by its sear preparatory to firing, the operating or handle end 10a of the cable 10 will be manually grasped by the operator and pulled outwardly to cause the plunger 8 to move in leftward direction, having reference to Fig. 1, to cause the plunger 8 to engage the gun bolt lug 4 so as to move the gun bolt in that direction until the latter is locked in cocked position by its sear. As soon as the gun bolt becomes locked in cocked position by its sear, the cable 10 may be released by the operator and the plunger 8 will immediately spring back in a rightward direction, respecting Fig. 1, to its noncharging position of engagement with the plug 21, as shown in said figure.

In guns of the type for which the charging device of the invention is particularly designed, the firing is automatic, so that the cocking device is operated only for initially moving the gun bolt to charged position in locked engagement with its sear, and the cocking device is not operated during firing of the gun or again until the gun bolt is required to be recocked, as when the gun becomes jammed or when ammunition has been exhausted and it is necessary to recharge the gun with ammunition.

It will be apparent that plunger 8, spring 9, guide member 7, abutment member 5 and the cable and pulley means comprising bracket 16, cable 10, and pulley 11, comprise a unitary gun cocking device which may be inserted in or removed from the charger receiver housing 2 as an integral unit, since the plunger 8 is associated with the other parts through the instrumentalities of the cable 10 and spring 9. The elements of the unit having been previously assembled as indicated, all that is necessary to be done in associating the unit in operative relation with the gun is to insert the abutment 5, guide 7, spring 9, and plunger 8 elements of said unit in the receiver housing 2 and lock the abutment member 5 in fixed position respecting the housing 2 by means of the set screw 6.

It will also be apparent that the plunger and spring elements may be readily preliminarily assembled in proper relation to the guide member 7 and abutment member 5 by threading the cable in a rightward direction, respecting Fig. 1 through the hollow boss 15, passage 5a, guide member 7, spring 9 and plunger 8 and securing the cable to the plunger 8 by means of the detachable connection, including ball fitting 14 and tapered member 13, as above described.

Having thus described our invention, what we claim as new and desire to secure by Letters Patent of the United States is:

1. A gun cocking device of the class described adapted for association with a gun having a breech and a breech bolt and having a housing arranged adjacent the breech, comprising, in combination, a supporting member adapted to be removably secured in said housing in fixed relation to the gun, said supporting member having an axial bore, a guide tube having an axial bore therethrough and secured to one end of said supporting member with its bore in alignment with

the bore in said supporting member, said guide tube being adapted to be within the housing when the supporting member is secured in the housing, a hollow plunger axially aligned with said guide tube and adapted for reciprocating movement in said housing along an axis parallel to the axis of movement of the bolt, said plunger being closed at one end and open at the other end, said plunger being adapted to engage the breech bolt when positioned in said housing, a coil spring coiled around said guide tube and entering said plunger to engage the closed end thereof, said spring also engaging said supporting member to urge the plunger away from said supporting member, and a flexible cable secured to said plunger and passing axially through said spring and said guide tube and said supporting member, said cable being operable to move the plunger toward the supporting member against the action of said spring, whereby the device may be detached from the gun and transported as a unit in that condition, and whereby the plunger will engage and move the gun bolt to cocked position when the supporting member is secured in fixed relation to the gun in said housing and the cable is operated as aforesaid.

2. A gun cocking device of the class described adapted for association with a gun having a breech and a breech bolt and having a housing arranged adjacent the breech, comprising, in combination, a supporting member adapted to be removably secured in said housing in fixed relation to the gun, said supporting member having an axial bore, a guide tube having an axial bore therethrough and secured to one end of said supporting member with its bore in alignment with the bore in said supporting member, said guide tube being adapted to be within the housing when the supporting member is secured in the housing, a hollow plunger axially aligned with said tube and adapted for reciprocating movement in said housing along an axis parallel to the axis of movement of the bolt, relative to the gun, said plunger being adapted to engage the breech bolt when positioned in said housing, said plunger being closed at one end and open at the other end, a coil spring coiled around said guide tube and entering said plunger to engage the closed end of the latter, said spring also engaging said supporting member to urge the plunger away from said supporting member, a flexible cable secured to said plunger and passing axially through said spring and said guide tube and said supporting member, and a pulley rotatably mounted on said supporting member at the opposite side thereof from said guide tube, said cable being trained over said pulley and operable to move the plunger toward the supporting member into telescoping relation with the guide tube against the action of said spring, whereby the supporting member may be detached from the gun and the device transported as a unit in that condition with all the elements carried by said supporting member, and whereby said plunger will engage and move the gun bolt to cocked position when the supporting member is secured in fixed relation to the gun in said housing and the cable is operated as aforesaid.

3. A gun cocking device of the class described adapted for association with a gun having a breech and a breech bolt and having a housing arranged adjacent the breech, comprising, in combination, a supporting member adapted to be

removably secured in said housing in fixed relation to the gun, said supporting member having an axial bore, a guide tube having an axial bore therethrough and secured to one end of said supporting member with its bore in alignment with the bore in said supporting member, said guide tube being adapted to be within the housing when the supporting member is secured in the housing, a hollow plunger axially aligned with said tube and adapted for reciprocating movement in said housing along an axis parallel to the axis of movement of the bolt relative to the gun, said plunger being closed at one end and open at the other end, said plunger being adapted to engage the breech bolt when positioned in said housing, a coil spring coiled around said guide tube and entering said plunger to engage the closed end of the latter, said spring also engaging said supporting member to urge the plunger away from said supporting member, a flexible cable secured to said plunger and passing axially through said spring and said guide tube and said supporting member, and pulley means associated with said supporting member and comprising a pulley over which the cable is trained, a pulley block rotatably mounted on said supporting member at the opposite side thereof from said guide tube, said pulley block being mounted for rotation relative to said supporting member about an axis parallel to the axis of said tube, said pulley being mounted on said block for rotation about an axis transverse to the axis of rotation of said block, said cable being operable to move the plunger toward the supporting member into telescoping relation with the guide tube against the action of said spring whereby the supporting member may be detached from the gun and the device transported as a unit in that condition with all of the elements carried by said supporting member, and whereby said plunger will engage and move the gun bolt to cocked position when the supporting member is secured in fixed relation to the gun in said housing and the cable is operated as aforesaid.

4. A gun cocking device of the class described adapted for association with a gun having a breech and a breech bolt and having a housing arranged adjacent the breech, comprising, in combination, a supporting member adapted to be removably secured in said housing in fixed relation to the gun, said supporting member having an axial bore, a guide tube having an axial bore therethrough and secured to one end of said supporting member with its bore in alignment with the bore in said supporting member, said guide tube being adapted to be within the housing when the supporting member is secured in the housing, a hollow plunger axially aligned with said tube and adapted for reciprocating movement in said housing along an axis parallel to the axis of movement of said bolt, said plunger being closed at one end and open at the other end, said plunger being adapted to engage the breech bolt when positioned in said housing, a coil spring coiled around said tube and entering said plunger to engage the closed end of the latter, said spring also engaging said supporting member to urge the plunger away from said supporting member, a flexible cable secured to said plunger and passing axially through said spring and said guide tube and said supporting member, and pulley means associated with said supporting member and comprising a pulley over which the cable is trained, a bearing element fixed to said supporting member on the opposite side thereof from said guide tube, said bearing

element having a bore therethrough in axial alignment with the bore in said supporting member, said bearing element having an annular groove therein, a pulley block rotatably mounted on said bearing element, means on said block engaging in said groove, and means for locking said block in fixed rotational position with respect to said bearing element, said pulley being mounted on said block for rotation about an axis transverse to the axis of rotation of said block, said cable being operable to move the plunger toward the supporting member into telescoping relation with the guide tube against the action of said spring, whereby the device may be detached from the gun and transported as a unit in that condition with all of the elements carried by said supporting member, and whereby the plunger will engage and move the gun bolt to cocked position when the supporting member is secured in fixed relation to the gun in said housing and the cable is operated as aforesaid.

5. A gun cocking device of the class described, adapted for association with a gun having a breech and a breech bolt and having a housing arranged adjacent the breech, comprising, in combination, a supporting member adapted to be removably secured in said housing in fixed relation to the gun, said supporting member having an axial bore, a guide tube having an axial bore therethrough and secured to one end of said supporting member with its bore in alignment with the bore in said supporting member, said guide tube being adapted to be within the housing when the supporting member is secured in the housing, a hollow plunger axially aligned with said tube and adapted for reciprocating movement in said housing along an axis parallel to the axis of movement of said bolt, said plunger being closed at one end and open at the other end, said plunger being adapted to engage the breech bolt when positioned in said housing, a coil spring coiled around said guide tube and entering said plunger to engage the closed end thereof, said spring also engaging said supporting member to urge the plunger away from said supporting member, a flexible cable, said plunger having a tapered socket in its closed end, and means for detachably securing said cable to said plunger and comprising a tapered member receivable in said socket and having an axial bore therethrough and a radial slot extending from end to end of said tapered member and communicating with said bore and adapted to permit insertion of said cable therethrough into said bore, said cable having an enlarged abutment member thereon, the bore of said tapered member having an enlarged portion at one end thereof to receive said cable abutment member, and the remainder of the bore of said tapered member being smaller than the cable abutment member, said cable passing axially through said spring and said guide tube and said supporting member, said cable being operable to move the plunger toward the supporting member into telescoping relation with the guide tube against the action of said spring, whereby the device may be detached from the gun and transported as a unit in that condition with all of the elements carried by said supporting member, and whereby the plunger will engage and move the gun bolt to cocked position when the supporting member is secured in fixed relation to the gun in said housing and the cable is operated as aforesaid.
